UNITED STATES PATENT OFFICE.

CARL F. GERLINGER, OF DALLAS, OREGON.

SPARK CONSUMER.

Application filed October 4, 1926. Serial No. 139,527.

This invention relates to spark arresters or consumers and has special reference to a device of this character particularly adapted for use on oil or coal burning locomotives, steam shovels, donkey engines, or any other machine having a smoke exhaust or stack.

One object of the invention is to provide an improved spark consumer so constructed that the exhaust, smoke, and the like, leaving the stack or pipe, strikes a series of plates and deflectors, causing said exhaust to change its direction and when in doing so any foreign particles such as carbon, sand scale, brick, etc. strike said plates and deflectors which pulverize same and in so doing fire is extinguished upon same leaving stack or pipe.

A second object of the invention is to provide a novel spark consumer which does not affect the steaming, or cause any back pressure, this being overcome in the design of same.

A third object of the invention is to provide a consumer in which every part may be adjusted so that deflectors and the like can be placed at the most efficient position, and the maximum results obtained in each individual case.

A fourth object of the invention is to provide a novel consumer which has no screen to clog up or burn out since in many cases, where screens have been used, holes have been punched through on account of steaming thus causing a back pressure, especially after being in use for a time.

A fifth object of the invention is to provide a novel consumer in which the operator's view is clear at all times, as the exhaust steam, smoke and the like rises above the stack and is not held down by back pressure.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a plan view of the device.

Figure 2 is a section on the line 2—2 of Figure 1.

Figure 3 is a section on the line 3—3 of Figure 2.

The device is intended to be mounted on the ordinary smoke stack 10 and in order to secure the device in position there is provided a split stack clamping ring 11 of angular formation in cross section and having end flanges 12 through which passes a clamp bolt 13 by means of which the ring is clamped on the stack. At intervals around this ring there are provided bosses 14 through which extend the vertical supporting rods 15 which are suitably threaded for purposes presently to be explained. On each of these rods there is mounted a supporting lug 16 which is adjustable vertically of the rod and these lugs may either be separate pieces or may be in the form of a continuous ring as may be desired. On each rod 15 is screwed a pair of adjusting nuts 17, one being above and the other below the lug and by means of these nuts the lugs are positioned to engage the top edge of the stack 10 thereby holding the entire structure in proper position on said stack.

The lower ends of the rods 15 pass through a flange 18 on the lower end of a deflector cylinder or bowl 19 which curves outwardly and upwardly from the ring 11, nuts 20 serving to hold the bowl in position on the ring. The rods 15 also pass through bosses 21 formed on a frusto-conical inside deflector 22 which is vertically adjustable on the rods and secured in adjusted position by adjusting nuts 23.

On the upper ends of the rods is mounted a hood 24 in the form of a ring having its inner portion or body arcuate in cross section with the concave side downward. The outer portion of this hood is curved downwardly and inwardly beneath the body as at 25 to form an inwardly open annular trough and the hood and parts carried thereby are adjustable vertically on the rods 15 and are held in adjusted position by nuts 26. Below the hood, adjacent its inner edge are spacers 27 and similar spacers 28 are located above the hood in alignment with the spacers 27. Bolts 29 pass through the hood and these spacers and on the lower ends of these bolts is mounted a core deflector 30, the under surface of which is in the form of an astroid of revolution thus resembling an inverted cone with convex sides. On the upper ends of the bolts is mounted a segmento-spherical deflector disk 31.

By this construction there is formed between the members 30 and 31 a casing open

2

at its sides above and below the member 24. It will also be noted that the top edge of the bowl 19 extends in spaced concentric relation about the member 24 slightly above 5 its greatest diameter. Beneath the annular space thus formed there is secured to the inside of the bowl an inverted frusto-conical deflector ring 32.

Obviously, the various adjustments provided permit setting the posts to suit the existing conditions relating to normal volume and pressure of the gases of combustion, steam and the like flowing up the stack. Also the arrangement of baffles or 15 deflectors is such that no hot sparks or other hot solid particles passing out of the stack can escape from the spark consumer.

There has thus been provided a simple and efficient device of the kind described 20 and for the purpose specified.

Having thus described the invention, what is claimed as new, is:

1. In a spark consumer, a main bowl member adapted to surround a stack, means 25 to support said member on a stack, an annular hood having an inwardly turned outer edge extending beneath the body thereof, said hood being positioned within the upper part of the bowl in inwardly spaced concentric relation thereto, a core deflector having a central depending point and spaced 30 below the opening in the annular hood to

close direct passage of fluid therethrough, a deflector disk spaced above said opening, a frusto-conical inside deflector spaced below the outer portion of the hood, and an inverted frusto-conical deflector ring fixed within the bowl below the space between the bowl and hood. 35

2. In a spark consumer, a main bowl member adapted to surround a stack, means to support said member on a stack, an annular hood having an inwardly turned outer edge extending beneath the body thereof, said hood being positioned within the upper 45 part of the bowl in inwardly spaced concentric relation thereto, a core deflector having a central depending point and spaced below the opening in the annular hood to 50 close direct passage of fluid therethrough, a deflector disk spaced above said opening, a frusto-conical inside deflector spaced below the outer portion of the hood, an inverted frusto-conical deflector ring fixed 55 within the bowl below the space between the bowl and hood, rods extending upwardly from the supporting means and having the inside deflector and hood independently adjustable thereon, and means to hold the inside deflector and hood in adjusted positions. 60

In testimony whereof I affix my signature.

CARL F. GERLINGER.
